United States Patent Office

Des. 177,586
Patented May 1, 1956

177,586

CASE

Richard C. J. Palson, Medfield, Mass.

Application November 22, 1955, Serial No. 38,993

Term of patent 14 years

(Cl. D58—12)

Fig. 1.

Fig. 3.

Fig. 2.

Figs. 1, 2 and 3 are perspective views of the case with the cover closed;

Fig. 4 is a perspective view of the case with the cover open;

Fig. 5 is a top plan view of the case with the cover open; and

Fig. 6 is a sectional view of the case taken on line 6-6 of Fig. 5.

This application is a continuation-in-part of my co-pending applications, Serial Nos. D-27,657 and D-27,658, both filed on November 18, 1953, now abandoned.

I claim:

The ornamental design for a case, substantially as shown.
